LABORATORY CABINET

John P. Salsgiver, West Acton, Mass., assignor to United Technical Corporation, West Concord, Mass.

Filed Dec. 18, 1969, Ser. No. 20,561

Term of patent 14 years

Int. Cl. D6—01

U.S. Cl. D16—2

FIG. 2.

The rear portions of the cabinet comprise flat, plain, and unornamented surfaces.

FIG. 1 is a perspective view of a laboratory cabinet showing my new design;

FIG. 2 is a view in side elevation.

I claim:

The ornamental design for a laboratory cabinet, as shown and described.
